UNITED STATES PATENT OFFICE.

FRED J. SCHRANK, OF AKRON, OHIO, ASSIGNOR TO THE STANDARD TRAFFIC MARKER COMPANY, OF WICHITA, KANSAS, A CORPORATION OF KANSAS.

TRAFFIC SIGN.

Application filed December 3, 1926. Serial No. 152,354.

This invention relates to traffic signs for use on streets or roads for indicating boulevard stops, railroad crossings, schools or other warning signals by which the driver 5 of a vehicle will be directed as to how he should proceed. This case is a continuation in part of application Serial No. 4,669, filed January 26, 1925.

The general object of the invention is 10 to provide an effective sign having the desired warning legend thereon which will be directly in the path of the vehicle and, accordingly, which the driver cannot fail to see, yet will not obstruct movement of 15 vehicles over the street, road or pavement in any way, the sign to be capable of yielding in all directions under the load of a vehicle passing thereover.

Particularly the invention is directed to 20 a sign of flexible, resilient, weather-proof material adapted to be mounted in the street or road so as normally to project upwardly therefrom in the path of vehicles and to yield under the weight of the vehicle which 25 may happen to pass thereover, no matter from what direction the sign happens to be engaged and to resume its normal position after the vehicle passes thereover.

A further object of the invention is to provide 30 an effective means for mounting such signs in roads or pavements.

A further object is to provide means for mounting the sign from which the sign 35 may be readily removed for replacement when worn out or broken and, in addition, to provide a sign so formed as to permit of ready mounting or removal from said means.

The foregoing and other objects are 40 obtained by the traffic sign construction illustrated in the accompanying drawings and described below. It is to be understood that the invention is not limited to the specific form thereof shown and described.

Of the accompanying drawings,

Figure 1 is a front elevation of a sign embodying the invention shown mounted in a pavement;

Figure 2 is a plan thereof;

Figure 3 is a perspective view of the sign per se;

Figure 4 is a section on line 4—4 of Figure 1; and

Figure 5 illustrates the action of the sign 55 under the load of a vehicle.

Referring to the drawings, the numeral 10 designates a sign of highly flexible, resilient, weather-proof material such as vulcanized rubber compounded to be of a toughness corresponding to that employed 60 in tire treads and vulcanized either with or without textile or other reinforcements therein. The sign 10 preferably is a comparatively thin sheet of rubber 11 of any suitable shape and, to facilitate replaceable 65 mounting thereof, may have a ledge of rubber 12 integrally formed on its lower edge. A legend for imparting any desired warning is provided on the upper portion of sheet 11 as at 13 in any suitable manner. 70 The sign is thus adapted to be embedded to a substantial depth in a pavement with the portion carrying the warning legend normally projecting upwardly therefrom.

The preferred type of mounting for the 75 sign comprise a box-like frame of suitable material, such as wood, metal plates, etc., including front and back members 14 and 15 and end members 16 and 17 adapted to be embedded in concrete, asphalt or other 80 plastic medium capable of hardening to secure the frame in the pavement. A portion of a completed pavement can be removed for embedding the sign therein or it may be embedded therein during construction of the pavement. 85

The front and back members 14 and 15 of the frame are spaced apart approximately the thickness of the sheet 11 plus the width of ledge 12, the ends 16 and 17 preferably just clearing the ends of the sign and the depth of the frame being approximately one-half the height of the sign 10. The frame accordingly defines an elongated slot 18 in the pavement into which sign 10 may 95 be inserted. To retain the sign 10 removably in place a clamping bar 19 is employed of a length adapted to fit between the ends 16 and 17 of the frame with space indicated at 20 for the insertion of a tool to engage 100 the end of the bar to remove it, the bar being of a thickness somewhat greater than the width of the space between the portion of the sign above the ledge 12 and the front member 14 of the frame, and the height of 105 the bar 19 being less than that of the frame by the height of the ledge 12. The upper edges of frame member 15 and bar 19 against sign 10 are preferably of curved formation so as not to cut into the rubber of the sign 110.

when it is flexed. To mount a sign 10 in place, the lower edge is inserted in slot 18 until it rests upon the bottom thereof. The bar 19 is then forced downwardly into the slot 18 in front of the sign onto the ledge 12, compression of the rubber of the sheet 11 serving to hold the sign in place. To remove a sign, clamping bar 19 may be first pried out of the slot by inserting a tool across an end of the frame into the space 20 against one end of the clamping bar. The sign 10 can then be lifted out of the slot.

In use the sign is directly in the path of vehicles passing along the roadway where a driver cannot fail to see it. If a driver should happen to guide one of his wheels over the sign it will flex downwardly easily without offering sufficient resistance or obstruction to the travel of the vehicle to be appreciable to the driver or to result in accidents from skidding or other causes. Due to the resilience of the sign it will immediately spring upwardly to its normal position after the load is removed therefrom. It will flex under the load of a vehicle no matter what the angle of approach may be and it will not injure vehicle tires in any way.

Modifications of the invention may be resorted to without departing from the spirit thereof or the scope of the appended claims.

What is claimed is:

1. A traffic sign construction comprising a frame embedded in a pavement to define an elongated slot therein, a sign of flexible, resilient, weather-proof sheet material adapted to be inserted in said slot so as to project upwardly above the pavement, said sign having an integral ledge formed along the lower edge thereof, and means for securing the sign in said slot comprising a clamping bar adapted to be force-fitted between the sign and one frame member onto said ledge, said bar being sufficiently of lesser length than the slot to admit a prying tool into the slot into engagement with one end thereof.

2. A traffic sign construction comprising a frame embedded in a pavement to define an elongated slot therein, a sign of flexible, resilient, weather - proof sheet material adapted to be inserted in said slot so as to project upwardly above the pavement, said sign having an integral ledge formed along the lower edge thereof, and means for securing the sign in said slot comprising a clamping bar adapted to be force-fitted between the sign and one frame member onto said ledge.

3. A traffic sign construction comprising a frame embedded in a pavement to define an elongated slot therein, a sign of flexible, resilient, weather-proof sheet material adapted to be inserted in said slot so as to project upwardly above the pavement, and means for securing the sign in said slot comprising a clamping bar adapted to be force-fitted be-

tween the sign and one frame member, said bar being sufficiently of lesser length than the slot to admit a prying tool into the slot into engagement with one end thereof.

4. A traffic sign construction comprising a frame embedded in a pavement to define an elongated slot therein, a sign of flexible, resilient, weather-proof sheet material adapted to be inserted in said slot so as to project upwardly above the pavement, and means for securing the sign in said slot comprising a clamping bar adapted to be force-fitted between the sign and one frame member.

5. A traffic sign construction including means providing a slot in a road or pavement, a sign of flexible, resilient, weather-proof material adapted to be inserted in said slot so as to project upwardly therefrom and having traffic-directing indicia upon the upwardly projecting portion, and means for removably securing the sign in the slot.

6. A traffic sign comprising a sheet of flexible, resilient, weather-proof material partially embedded in a roadway so as normally to project upwardly therefrom and having traffic-directing indicia upon the upwardly projecting portion thereof.

7. A traffic sign comprising a sheet of rubber partially embedded in a roadway so as normally to project upwardly therefrom and having traffic-directing indicia upon the upwardly projecting portion thereof.

8. The combination with a roadway of a traffic sign partially embedded therein so as to project upwardly therefrom, said sign being of flexible resilient weatherproof material capable of flexing downwardly under the load of a vehicle passing thereover without appreciably obstructing passage of the vehicle.

9. In combination, a grooved ground-portion having curved bending shoulders at its edges and a flexible sign panel anchored in the groove bendable over the shoulders.

10. A traffic warning signal permanently attached to the road-way having a base member with its upper face substantially flush with the surface of the road-way and an embedded elastic display member extending upwardly therefrom.

11. A sign comprising a flexible panel and means for mounting said panel in the ground so as to project upwardly therefrom, including a frame and means for clamping said panel in said frame.

12. A device of the class described comprising a normally upstanding panel of inherently flexible material partly embedded in the ground so as to project upwardly therefrom, the projecting portion being capable of returning to its normal upright position after passage of an object thereover, and having indicia on the upwardly projecting portion thereof.
